US0D1107358S

(12) **United States Design Patent** (10) **Patent No.:** **US D1,107,358 S**
(45) **Date of Patent:** **** Dec. 23, 2025**

(54) **DUST BOX FOR CLEANING ROBOT**

(71) Applicant: **Beijing Roborock Technology Co., Ltd.**, Beijing (CN)

(72) Inventors: **Peng Xu**, Beijing (CN); **Baokui Zhang**, Beijing (CN); **Lifeng Gao**, Beijing (CN); **Xingxing Hu**, Beijing (CN)

(73) Assignee: **Beijing Roborock Technology Co., Ltd.**, Beijing (CN)

(**) Term: **15 Years**

(21) Appl. No.: **35/523,180**

(22) Filed: **Aug. 19, 2024**

(80) **Hague Agreement Data**

Int. Filing Date: **Aug. 19, 2024**

Int. Reg. No.: **DM/242213**

Int. Reg. Date: **Aug. 19, 2024**

Int. Reg. Pub. Date: **Dec. 6, 2024**

(30) **Foreign Application Priority Data**

Aug. 7, 2024 (CN) 202430499763.X

(57) **CLAIM**

The ornamental design for a dust box for cleaning robot as shown and described.

DESCRIPTION

1. Dust box for cleaning robot
2. Dust box for cleaning robot
- 1.1 : Front view
- 1.2 : Back view
- 1.3 : Left view
- 1.4 : Right view
- 1.5 : Top view
- 1.6 : Bottom view
- 1.7 : Perspective view 1
- 1.8 : Perspective view 2
- 1.9 : Perspective view 3
- 2.1 : Front view
- 2.2 : Back view
- 2.3 : Left view
- 2.4 : Right view
- 2.5 : Top view
- 2.6 : Bottom view

(Continued)

2.7 : Perspective view 1

2.8 : Perspective view 2

2.9 : Perspective view 3

The broken lines shown in the reproductions are for the purpose of illustrating portions of the dust box for cleaning robot and form no part of the claimed design. The portions of the design shown in white and surrounded by broken lines is for purpose of illustrating portions of the dust box for cleaning robot and form no part of the claimed design.

1 Claim, 18 Drawing Sheets
